UNITED STATES PATENT OFFICE

PAUL M. LUKOMSKE, OF FAIRFIELD, CONNECTICUT

SECTIONAL BOILER

Application filed April 25, 1932. Serial No. 607,239.

My invention relates to new and useful improvements in sectional water heaters of that type wherein a plurality of independently formed sections are used either as a hot water heater or steam boiler.

The object of the invention is to provide a novel construction of furnace that is especially adapted for burning oil, and wherein a series of flues are provided that extend through the length of the furnace so that an increased surface area of the boiler will be exposed to the flame and products of combustion from the fuel in a manner to better extract the heat therefrom.

15 A further feature of the invention is to first pass the fire through the upper sections of the furnace, and then down through its lower portions where the water is naturally coolest, and finally discharging the smoke out from the lower portion after the heat has practically all been extracted therefrom. By this arrangement, the products of combustion, as they pass from the combustion chamber, are exposed to the upper part 25 of the boiler where the water is naturally the hottest, and then when cooler passes down through the lower portion where the return incoming water is naturally cooler.

A further object of my invention is to design a furnace which is more or less elastic, that is to say, one which readily lends itself to the construction of boilers of different sizes and heating capacity, in which a suitable number of intermediate sections may be 35 employed in a way to form a longer or shorter boiler.

The essential and characteristic features of the invention are obviously susceptible of modification, the illustration shown in 40 the accompanying drawings being a preferred embodiment of the invention, as will be better understood from the following description wherein references made to the accompanying drawings of which

45 Fig. 1 shows a perspective view of my improved furnace, as it will appear when enclosed by a suitable sheet metal casing;

50 Fig. 2 shows a somewhat similar perspective view of the several cast metal sections assembled and secured together, as used in the

formation of my furnace, and preparatory to receiving the enclosing jacket shown in Fig. 1;

Fig. 3 shows a sectional plan view taken through the upper portion of the assembled 55 sections of the furnace, on line 3—3 of Fig. 2;

Fig. 4 illustrates perspective views of the several case metal sections or units of the furnace arranged in spaced relation and relative order so that when moved together, and 60 secured, will form a complete assembled furnace shown in Fig. 2;

Fig. 5 shows a central vertical longitudinal section taken on line 5—5 of Fig. 2;

Fig. 6 is a further sectional plan view 65 through the intermediate portion of the furnace, taken on line 6—6 of Fig. 2.

Fig. 7 shows a further sectional plan view through the lower portion of the assembled 70 units taken on line 7—7 of Fig. 2; and

Fig. 8 shows a detailed sectional view illustrating one of the sleeve connections employed in coupling the sections together.

Referring first to Fig. 4 of the drawings 75 wherein is illustrated five case-metal sections, as used in the construction of a boiler of specific capacity, are separately illustrated, it will be observed that the front section A and the rear section B are different in details of construction from each other, 80 and that the intermediate sections C, of which but three are shown, are alike in construction though different from either of the end sections. This obviously makes it practical to employ a greater or lesser number of the intermediate sections to form a boiler of greater 85 or lesser capacity.

Each of these sections forms in itself a water containing unit, and when assembled in series and secured together in the manner illustrated in Fig. 2, forms a common water chamber 10 by reason of the nipples connecting the upper and lower portions of the several sections. These assembled sections form a central longitudinal combustion chamber 90 and associated flues, service or feed pipe outlets 11, return inlets 12, tapped holes 13 for the attachment of an altitude gauge 14, and other tapped holes 15 for the attachment of try-cocks 16 and additional holes 17 for a 95 100

gauge glass 18, all of which are more or less employed in furnaces of this general type. The tapped hole 19 is for the attachment of an aquastat which is used as a safety device 5 for both hot water and steam heating. 20 represents an opening for application of a stack control, not shown, and 21 represents a further hole which serves as an outlet through which the boiler may be emptied. 10 If the boiler is used as a steam boiler, it would require a safety valve and other accessories common to that class of boiler, but which I have omitted from the drawings.

It will also be obvious that the assembled 15 unit, as shown in Fig. 2, may be covered in any preferred manner, and with any preferred material such as a preliminary coating of plastic or sheet asbestos that may or may not be covered with a sheet metal casing 22, 20 as illustrated in Fig. 1.

Referring first to the general construction of the heater, as shown in Figs. 1, 2 and 4, and formed of the several connected sections, 25 it will be noted that 23 represents the main combustion chamber which may or may not be lined with fire brick, not shown. The front end of the combustion chamber is enclosed with a closure frame 24 on which is hung a door 25. A gun type or rotary form 30 of oil burner 26, that may be of any preferred make, is positioned in a hole 27 of the frame and projected into the combustion chamber in the usual manner.

The several flues which will next be referred to, and which for the most part extend through different portions of the boiler, are produced by forming openings through and in the several sections, which are located so as to properly register one with another when 40 the sections are assembled in a way to form a continuous passage or flue from the combustion chamber backward and forward and vertically to the smoke outlet which is situated in the rear portion of the furnace.

45 Referring first to the front section A, it will be seen that it is provided with a large central opening 28 therethrough, which like similar openings 28 in the other sections, except the rear section B, serves to form the combustion chamber. The said rear section is, however, provided with a pocket 29, see 50 Figs. 4, 5 and 6, that is of a size and position to register with the opening 28 in the adjacent section, and thus serves to form the closed rear end portion of the combustion chamber.

The front section A, as well as the three intermediate sections C—C—C, are provided with a central opening 30 therethrough immediately above the combustion chamber 28 and adjacent the communicating upper side openings 31—31, which openings, like the combustion chamber openings, are similarly located and of like sizes and proportions so 65 as to register one with the other when the sec-

tions are assembled, and whereby a central upper longitudinal flue 32 is formed that extends through each of the sections A—C—C—C and into a pocket 33 of the rear section B, the forward end of the said flue 32 being open into the forward end of the combustion chamber through a vertical opening 34, see Figs. 4 and 5, and whereby the products of combustion from the combustion chamber flow up into the central longitudinal flue 32 and back into the pocket where it returns and comes forward, see arrow Fig. 3, into the longitudinal flues 35—35. The front end of said flues, as well as the other openings through the front section A, being closed by 80 the metal casing 22 and doors hung thereon, as shown in Fig. 1.

Each of the adjacent side faces of the several sections are provided with vertical concaved recesses on either side of the combustion chamber openings which, like the said openings and flues are proportioned and positioned to register with each other, see Fig. 6, when the sections are assembled, and for the purpose of forming a series of vertical flues 90 36 which extend down on either side of the combustion chamber from the before mentioned upper longitudinal flues 35 and connect with the lower outer longitudinal flues 37 that are formed by the openings 38 in the lower corner portions of the several sections. The two openings 38' through the front section A, see Figs. 4 and 7, are relatively wider than the openings 38 through the intermediate sections C so as to form a return into flue 39 from the longitudinal flue 37 formed by openings 40 through the intermediate sections C and rear section B. These openings in the last mentioned section B are deflected 95 inward to form a united smoke outlet or nipple 41 central of and in the lower rear portion of the furnace.

Each of the vertical flues is provided with a clean-out opening 42 through each portion of the adjoining sections, which openings are normally closed by doors 43, see Fig. 1. The upper flues 32 and 35 are provided with clean-out doors 44 while the lower flues 37 and 39 are also provided with clean-out doors 45. The connecting openings to insure a circulation of water through all the sections are preferably formed by a series of aligned holes 46 through both the central top portion of the furnace and the lower central portion, the customary form of nipples 47 being employed to insure a proper watertight connection as between the sections. The sections may also be secured together in the usual way by tie-rods 48, two of which extend across the top of the sections and engage holes in flanges of the front and rear sections while the lower rods are preferably located in the flues 39 and have their end portions engaged with the end sections, one end of the rods being 100 110 115 120 125 130

threaded and provided with a nut whereby sections may be drawn together.

It is to be noted that in the formation of applicant's boiler, he not only provides a larger number of flues that extend longitudinally through the furnace than is customarily found in cast metal types of boilers, but has arranged the same so that the products of combustion first pass and re-pass through the upper portion of the furnace above the combustion chamber and are then carried down upon opposite sides of the combustion chamber to longitudinal flues in the bottom portion of the furnace which again serve to carry the products of combustion forward and backward through the boiler.

It is also a feature of the design of applicant's boiler that all walls of the sections, which are exposed on the one side to the heat or products of combustion of the boiler, also serve as a wall for water in the furnace in a way to quicker consume all the heat from the smoke before it is discharged into the chimney and thereby more efficiently heat the water.

Having thus described my invention, what I claim and desire to secure by Letters Patent is:

1. A water heater comprising a series of metal sections secured together to form a common water container and having a centrally positioned elongated combustion chamber extended through all the sections, a central flue extended from front to rear above the combustion chamber, return flues also in the upper portion of the sections and on both sides of the central flue, two longitudinal side flues extending through the outer base portion of the united sections, a series of vertical flues on opposite sides of the combustion chamber and connecting the longitudinal side flues with the return flues, intermediate longitudinal flues communicating with the two longitudinal side flues, and also extending through the central portion of the base portions and terminating in a smoke outlet.

2. A water heater comprising a series of metal sections secured together to form a common water container and having a centrally positioned elongated combustion chamber, three flues extended from front to rear above the combustion chamber, one to direct the products of combustion rearward, and the other two to return said products forward, longitudinal flues extending through the base portion of the sections to direct the products of combustion forward, one or more longitudinal flues connected with said last mentioned flues and terminating in a rear smoke outlet, a series of vertical flues connecting certain of the lower longitudinal flues with the upper flues, all arranged to first pass the products of combustion through the upper part of the boiler twice or more and then through the lower part.

3. A water heater comprising a series of

metal sections secured together to form a common water container and having a centrally positioned elongated combustion chamber, three flues extended from front to rear above the combustion chamber, one to direct the products of combustion rearward, and the other two serving as longitudinal return flues, longitudinal flues in the base portion of the united sections below the combustion chamber to direct the products of combustion forward, one or more longitudinal flues connected with said last mentioned flues and terminating in a smoke outlet, vertical flues formed between the adjoining sides of the sections and connecting certain of the upper longitudinal flues with the lower flues, all arranged to first pass the products of combustion twice through the upper part of the boiler, then down through the side portions, and finally longitudinally through the lower part.

4. A water heater comprising a series of metal sections secured together to form a common water container and having a centrally positioned elongated combustion chamber, three flues extended from front to rear above the combustion chamber, one to direct the products of combustion rearward, and the other two serving as longitudinal return flues, longitudinal flues in the base portion of the united sections below the combustion chamber to direct the products of combustion forward, one or more longitudinal flues connected with said last mentioned flues and terminating in a smoke outlet, vertical flues formed between the adjoining sides of the sections and connecting certain of the upper longitudinal flues with the lower flues, clean-out openings also formed between the adjoining sides of the sections and communicating with said vertical flues.

5. A water heater comprising a series of metal sections secured together to form a common water container and having a centrally positioned elongated combustion chamber, four longitudinally arranged series of communicating water pockets in the upper part of the boiler and three longitudinal flues therebetween, one of said flues being in direct communication with the combustion chamber, an inner and outer pair of longitudinal flues in the lower part of the boiler having water pockets therebetween, and a series of vertical flues formed in the adjacent sides of the sections and connecting the upper outer flues with the lower outer flues.

6. A water heater comprising a series of metal sections secured together to form a common water container and having a centrally positioned elongated combustion chamber, four longitudinally arranged series of communicating water pockets in the upper part of the boiler and three longitudinal flues therebetween, one of said flues being in direct communication with the combustion

chamber, five longitudinally arranged series of communicating water pockets in the lower portion of the boiler, two pairs of longitudinal flues in the lower part of the boiler between the last mentioned series of associated water pockets one being an inner pair and the other an outer pair, and a series of vertical flues formed in the adjacent sides of the sections and connecting the upper outer flues with the lower outer flues.

10 Signed at Bridgeport in the county of Fairfield and State of Connecticut this 23rd day of April, A. D. 1932.

PAUL M. LUKOMSKE.
